Primary Examiner — Cynthia Ramirez*Assistant Examiner* — Jeremy S. Swartz(74) Attorney, Agent, or Firm — Squire Patent Consulting & IP Law LLC; Brendan E. Squire(57) CLAIM

The ornamental design for a hanger, as shown and described.

DESCRIPTION

FIG. 1 is a front perspective view of the hanger showing my new design;

FIG. 2 is a front elevation view thereof;

FIG. 3 is a rear elevation view thereof;

FIG. 4 is a left side elevation view thereof, the right-side elevation view being a mirror image thereof; and,

FIG. 5 is a top plan view, the bottom plan view being a mirror image thereof.

The broken lines in the drawings depict portions of the hanger that form no part of the claimed design.
